United States Patent Office.

J. R. HOFFMAN, OF FORT WAYNE INDIANA.

Letters Patent No. 92,191, dated July 6, 1869.

IMPROVEMENT IN SAW-MILLS.

The Schedule referred to in these Letters Patent and making part of the same.

To whom it may concern:

Be it known that I, J. R. HOFFMAN, of Fort Wayne, in the county of Allen, in the State of Indiana, have invented a new and useful Improvement in Saw-Mills; and I do hereby declare that the following is a full and exact description thereof, reference being had to the accompanying drawings, and the letters of reference marked thereon.

My invention relates to that kind of saw-mill where a band or belt-saw is used for sawing lumber, by passing the band-saw around two pulleys at the proper distance apart; and

It consists in the means used for guiding, or giving direction to that portion of the saw that is operating to saw the wood, and in the devices used for adjusting the upper pulley to give the saw the necessary position on the pulleys.

To enable others skilled in the art to make and use my invention, I will describe its construction and operation.

Figure 1 is a view of the rear elevation of the frame;

Figure 2 is a view at right angles of the same;

Figure 3 is a plan view of the adjustable saw-guide and its supports; and

Figure 4 is a sectional view of the same.

A, in the drawings, represents the frame which supports the operating-parts.

A', A'', and A''' are cross-beams for supporting the parts of the machine.

B is the main driving-shaft, and upon which is saw-pulley C.

B' is the shaft upon which pulley C' is hung.

D is a belt-saw, which passes around the pulleys C C'.

Shaft B', that carries saw-pulley C', is supported in an adjustable frame, c, and bears upon a box next the pulley-wheel C', on its under side, while the back end of the shaft is contained in a sliding support or box, a', upon a horizontal adjustable block, a.

Upon the sliding support a', and over the shaft B', and sliding on its upper end, is a keeper, b, which is a bearing for the rear end of said shaft B', when there is strain upon the saw D, which causes the shaft, at its rear end, to bear on its upper side, and against the keeper or sliding box, b.

The sliding support c is adjustable, and slides up or down in grooves cut in cross-beam A'' and adjustable block a, and is adjusted to strain the saw D, by means of the wedge c' sliding upon support A'', and underneath the sliding support c, as is fully shown in figs. 1 and 2.

Block a is adjusted horizontally, by means of holding-screws g' g, working in slots g g'.

The object of this arrangement and construction of devices is to guide the saw to be properly carried upon the pulleys C and C'.

Through that part of support C which is designated a, and the keeper or box b, goes a mortise, in such manner, that as the key b' is forced in, it raises the sliding box b upon its support a', which will affect the perpendicular position of wheel C', and thus change the position of the saw upon the pulleys C and C', so that the front line of the saw-teeth can be made to project, if necessary, in front of the pulleys, or at any position desired upon the pulleys.

Heretofore, a great difficulty has been experienced in giving the proper direction to that part of the saw which is doing the work in the wood, and to maintain the proper position, and have the saw cut through large timber without variation, and in sawing curved lumber, it is necessary to sometimes change the direction that the saw shall have between the pulleys.

To produce results never before attained in the use of band-saws, and to overcome the difficulties above enumerated, I have constructed a saw-guide, so that, through its influence, the saw-plate can be changed in its direction without changing the right line at the points of the teeth, and only the back of the saw is moved at the right or the left to a greater or less extent, as may be desired.

The saw-guide E', that I have constructed, rests upon a support, E, bearing upon and firmly attached to support A', or to other convenient means of firm support.

This guide E' is of metal, or other material that will answer the purpose, and is constructed with a circular slot, f', in the supporting-plate, and has a holding-screw, f, in said slot.

From the under side of the base-plate is a circular projection, e, in dotted lines, as seen in dotted lines in fig. 3.

Above the plate is another projection, and in both the circular and upper projection is a slot of the width to receive the thickness of the saw-plate, with the front edge of the upper projection just over the centre of the circular projection on the lower side of the guide-plate, which front of the upper projection should be the point at which the points of the teeth of the saw should be made to correspond whenever the guide is used to change the saw; then, by giving the plate at the rear of the saw, a change, either one way or the other, the slot e', in the guide, will not change the line of the saw at the points of the teeth, because there is no motion at that point, but will change the back of the saw, by forcing it, by means of the slot in the guide, to go either way, as may be desired, and thus change the direction of the saw-plate more or less at will, when the holding-screw is turned down and clamps the guide in its position.

The pulley-wheels C and C' are covered with India rubber of sufficient thickness to prevent the set in the saw-teeth being destroyed.

With this construction and arrangement, I am ena-

bled to adjust the saw to work easily upon the pulleys, without the use of guides at the back or sides, and thus lessen the friction, and give more power to the saw for cutting the wood.

I am aware that many devices have been used for adjusting the saw to run upon the pulleys, and to give direction to the saw, but none of them have the devices that I have described as new and of my invention.

Having thus described my invention,

What I claim, and desire to secure by Letters Patent, is—

1. The combination of the shaft-support *c* with the

adjusting-block *a'*, slots *g'*, and screw *g*, constructed and arranged to operate in the manner and for the purpose substantially as described.

2. The combination of the shaft-support *c* with the sliding keeper or box *b*, and adjusting-key *b'*, all constructed and arranged to operate in the manner and for the purposes substantially as described.

3. The guide *E'*, constructed in the manner and for the purpose described.

J. R. HOFFMAN.
